RACK

Emmerich T. Igler, New York, N. Y.

Application February 26, 1949, Serial No. 78,625

6 Claims. (Cl. 211—90)

1

In a generic sense, the invention relates to an improved construction for the convenient and hygienic storing and suspension of various articles.

Specifically, the invention comprehends the provision of improvements in compartmented racks, and means for suspending ties, belts and other articles in a sanitary, protected and well-ordered manner.

Heretofore, various expedients have been employed by the male of the species in storing and keeping shoes, slippers, ties and other wardrobe articles in a closet. Racks are often used for shoes, and hangers for ties; handkerchiefs are usually kept in a bureau drawer so that, in assembling the wardrobe for dressing, several places must be explored, including the murky atmosphere of the floor of the closet. The latter tends to collect dust and be unsanitary, and shoes are apt to fall off or skew on the racks. The conventional methods of storing are at best "hodge podge."

And with the female of the species other expedients are employed. Belts are usually hung in one place, shoes stored in another; handbags and accessories, such as gloves, are kept heterogeneously—and assembling the wardrobe is a task.

It is one object of the invention to provide a compact, composite rack where a plurality of different articles, heretofore placed in different locations, may be stored.

It is another object to construct a composite shelving wherein articles such as shoes and neckties, handkerchiefs, and slippers, usually kept in different places for hygienic reasons, may be stored in one locale without one specie of article, i. e. ties, coming in contact with another specie, viz: shoes.

Another object is the provision of shelving wherein shoes may be kept individually in a neat, separated manner, and placed in and taken from the shelving expeditiously.

A further object is the provision of the optimum in shelving space.

Still another object is a composite shelving which can be readily rearranged to accommodate different species of articles.

In its broader aspects, my invention provides a composite, convertible, compartmented shelving, easily manufactured of relatively inexpensive materials, adapted for the expeditious, sanitary, separated storing of a multiplicity of articles of the male and female wardrobe, to which there is selective access.

2

Other objects will be apparent from a reading of the detailed description and drawings.

In the drawings:

Fig. 1 is a front elevational view of the compartmented, composite rack.

Fig. 2 is an enlarged vertical section of Fig. 1 along lines 2—2 of Fig. 1.

Fig. 3 is an end view of Fig. 1 and

Fig. 4 is a perspective view of the rack showing same in use, with a few wardrobe items shown in outline, positioned on the rack.

Fig. 5 is a sectional view similar to Fig. 2 but it shows a rear wall.

Fig. 6 is a perspective view of a modification of my compartmented, composite rack.

Fig. 7 depicts a perspective view of a modification of the rack designed for the feminine wardrobe.

Fig. 8 is a fractional perspective view of a section of a lower rack element showing trackway.

Fig. 9 is a perspective view of a supplemental rack element.

Fig. 10 shows a detail of an arm of a supplemental rack element.

Fig. 11 illustrates the manner in which the supplemental rack element is slidably received on the trackway.

Fig. 12 is a perspective view of the inclined shoe shelf of the modification.

Fig. 13 shows the upper guide track.

Fig. 14 is the L shaped member attached to the nested supplemental rack.

Fig. 15 is an end view of the inclined shoe shelf.

Similar numerals refer to similar parts throughout the several views.

The composite, compartmented rack, denoted by the numeral 10, comprises a pair of spaced, vertical frames 11, united at intervals by a rack member 12 and a plurality of shelves 13, 14, 15.

Rack member 12, the uppermost, unites frames 11 transversely, extends in a vertical plane and is provided with projecting pins 16 anchored in the rack 12, for suspending ties, belts or other articles therefrom.

Shelf 13, the outer edge of which has an upturned flange, is of a length equal to the spacing of the frames, does not extend from the front to rear plane, but from the front to a plane inward from or terminating short of the rear of the composite rack.

Shelves 14, 15 are also of a length equal to the spacing of frames 11 and extend from the front to rear plane of said frames.

Spaced inwardly from the rear plane of the frames 11, and diagonally downward from rack

member 12 I provide wall 17, the opposite sides thereof joined to frames 11, the lower end abutting the upper surface of shelf 14 and the rear of shelf 13 and terminates diagonally upwardly from the upper edge of shelf 13, to define, in conjunction with the door or member on which the composite rack is suspended, and the adjacent sides of frame 11 and shelf 14, what I style a well 18, into which articles, such as neckties, belts, and the like may be suspended from rack member 12, in an orderly, sanitary and protected manner. Selected access is provided to the articles suspended from rack member 12, in addition to the protection afforded to the contents by the wall 17, which separates said articles from those stored in the compartments on the opposite side.

Shelf 13 may be provided with partitions, as at 19, forming compartments 20, for storing articles such as handkerchiefs, socks and the like.

Removable partitions 21, accommodated in tracks 22, provide compartments 23, between shelves 13 and 14, while partitions 24, fitting in tracks 25, form compartments 26 between shelves 14 and 15.

Across compartments 23 and 26 I detachably mount keeping bars 27 in slotted brackets 28 on the vertical frames 11.

For suspending my composite rack from the door of a closet or the like, brackets 29 are affixed to the upper extremities of frame 11.

In the embodiment illustrated in Figs. 1-4, ties or other articles may be suspended in the well behind wall 17, protected from the shoes or other articles in compartments 23. In Fig. 5, one modification of my invention, I show a second wall 30 formed co-extensive with the rear plane of frame 11, so that the articles suspended from rack member 12, will hang in a well, formed by the rear of wall 17, the back 30, and the adjacent inner sides of the frame 11.

The compartments 23, 26 are each devised for containing one pair of shoes, upright, or if desired, the lower partitions 24 may be removed and linens, books, phonograph records, spirituous beverages or other articles stored, with shoes only placed in the medial compartments 23.

The keeping bars 27 afford expeditious access to the compartments 23, 26, as well as to prevent the dislodgement of the stored articles at all times and particularly when the closet door from which the composite rack 10 is suspended, is slammed.

I thus provide in one conveniently accessible repository, space for storing virtually all those components of the wardrobe heretofore stored in a multiplicity of places, i. e. tie rack, bureau drawer, floor of the closet. For the composite rack furnishes the well 18, in which ties, for example, are suspended, protected from contact with the dirt of shoes which may be stored in compartments 23 as well as from those articles which may be kept in compartments 20 and those below in compartments 26.

In Fig. 6 I show another modification wherein rack member 40 is movably mounted in track-way 31 for movement through openings 32 provided in frames 11 to permit movement either right or left of the frames depending on whether the composite rack is suspended from a door hinged at one side or the other.

Well 18 is also provided in this modification, with the articles selectively removable from the rack member 40 when the rack member is moved either right or left from the well 18.

In Figs. 7 through 15 I have illustrated a modi-

fication wherein the composite rack is designed particularly for the storing of accessories for the feminine wardrobe.

Herein, from rack member 12 and behind wall 5 17 are suspended articles such as belts, while shelves 13, 14, 15, 33 are flanged at their outer or front edges.

On shelf 13 may be placed gloves, jewelry, handkerchiefs, and stockings.

10 Beneath, on shelf 14 is provided space for handbags, with additional room for more handbags, or other articles on rack 15.

In this modification frames 11 are extended and beneath lower shelf 33 I mount guide tracks 15 34—see Fig. 13, which receive L-shaped members 35, fitted to the upper edges of arms 36 of a supplementary shelf 37. Additional shelves may be nested below each other if desired.

Further, in this modification I furnish inclined 20 shoe shelf 38 with heel catch 39, fitted behind the flange of shelf 33.

The composite rack may be modified to suit the particular requirements of the wardrobe, masculine or feminine; the keeping bars may be 25 omitted as in Fig. 6; the separating partitions 21, 24 removed as desired, and the number of rack members 40 or shelves 13, 14, 33, 37 increased or decreased, maintaining, however, wall 17 and/or wall 30, in all modifications to provide 30 the maximum possible hygienic storing and suspension of articles in the well 18 separated from contact with articles in the other compartment.

The rack may be prefabricated from plywood or other wood product; it may be stamped of 35 steel, aluminum or other metals, or of man-made materials, such as plastics.

The composite rack is a boon to the multitude of persons whose wardrobe is stored in a number of places, for now in one easily accessible 40 location can be kept the most necessary components. Groping on the floor for shoes will be a thing of the past; articles heretofore soiled before wearing by contact with shoes will be obviated. The close quarters of the metropolitan centers, with millions living in small apartments 45 with limited space, will be afforded the modicum of convenience in wardrobe keeping.

I reserve the right to such changes or modifications as may come within the scope of the appended claims.

50 I claim:

1. In a compartmented rack, the combination of a pair of spaced, parallel and vertical supporting frames forming side members, a rack member mounted on and extending between the tops 55 of the frames, a plurality of transversely extending shelves of a length equal to the spacing of said frames and mounted on the frames, at least one shelf terminating short of the front to rear plane of said frames, a wall mounted on and 60 extending between the side members and behind said last-mentioned shelf, whereby a well is formed by said wall and a part of the inner walls of the side members, and below the said rack member.

65 2. A composite, compartmented rack for suspension from a door including at least a pair of spaced, supporting, vertical frames, a plurality of transverse shelves of a length equal to the spacing of said frames mounted on and extending 70 between the frames, at least one rack member mounted vertically at the top and rear of said frames and having means for suspending articles therefrom, at least one of the transverse shelves extending from a front to rear plane, at least one transverse shelf extending from the front and

75

terminating short of the rear plane of the frame, a wall mounted on the frames and extending upwardly from the shelf which extends from front to rear plane, and behind the shelf which terminates short of the rear plane, to form a protected well between the side members, the said wall and the door from which the rack is suspended.

3. A composite, compartmented rack for suspension from a wall and for storing and suspending articles including at least a pair of spaced, supporting vertical frames, a plurality of transverse shelves equal to the spacing of the frames and mounted thereon, at least one rack member mounted vertically at the top and extending between the frames and having means for suspending ties, belts and thin articles therefrom, at least one of the transverse shelves extending from front to rear plane, at least one shelf extending from the front and terminating short of the rear plane of the frame, a wall mounted vertically between the frames and extending upwardly behind the shelf which terminates short of the rear plane to form a well between the side members, the said wall and the wall from which the rack is suspended.

4. A compartmented rack as described in claim 2, wherein the transverse racks are provided with dividing partitions and front keeping bars.

5. A compartmented rack as described in claim 2, wherein lower racks are provided with partitions and keeping bars, forming compartments for the storing of wardrobe articles, and articles suspended from the top transverse rack are stored in a hygienic manner separated from contact with other wardrobe articles stored in the compartments.

6. A composite, compartmented rack for attachment to a wall, door, or partition for selectively storing shoes, storing and suspending other wardrobe articles, including: a pair of spaced,

vertical, supporting frames; a plurality of transversely extending rack components mounted on and extending between the top and the bottom of the frames and intermediately of the top and bottom between the frames; a wall-member mounted on and extending between the frames above one of said components and spaced inwardly from the rear of said frame; dividing partitions between the rack components positioned between the bottom of the frame and those extending in parallelism thereabove and below the rack component extending between the top of the frames, whereby compartments are formed for selectively storing shoes in an upright position, and a well is formed between the wall, door, or partition, and the wall-member for protecting wardrobe articles therein adapted to be suspended from the transversely extending rack component mounted between the top of the frames.
